UNITED STATES PATENT OFFICE.

GEORGE H. THAYER, JR., OF PLYMOUTH, INDIANA.

HYDROCARBON-BURNER.

No. 895,596.

Specification of Letters Patent.

Patented Aug. 11, 1908.

Application filed August 4, 1906. Serial No. 329,158.

To all whom it may concern:

Be it known that I, GEORGE H. THAYER, Jr., a citizen of the United States, residing in Plymouth, in the county of Marshall and 5 State of Indiana, have invented a new and useful Improvement in Hydrocarbon-Burners, of which the following is a specification.

This invention relates to improvements in hydro-carbon burners, or apparatus in which 10 oil and water are vaporized and their vapors intermixed and superheated for combustion; and the invention consists in certain features of construction whereby superior vaporization, intermixing of the gases, and superheat- 15 ing of the mixture are attained; together with such other novel features of construction and operation as I hereinafter set forth.

In the accompanying drawing forming a part of this specification, Figure 1 is a side 20 view of the complete device with its incasing pan shown in longitudinal section; Fig. 2 is a top plan view of the complete device, includ- 25 ing the incasing pan shown in section in Fig. 1; Fig. 3 is a top plan view of the device as sectioned on the line 3—3 of Fig. 4; and Fig. 4 is a transverse sectional view on the line 30 4—4 of Fig. 1. Fig. 5 is a section of one of the drop forming devices.

Like reference numerals indicate like parts 30 in all of the figures.

Supply pipes 10 and 11 lead respectively from supply tanks, not here shown, of, re- 35 spectively, water and fuel oil, through drop forming devices 12 and 13, whereby the sup- 40 ply may be conveniently and exactly regu- 45 lated, to the vaporizing tubes 14 and 15. These vaporizing tubes 14 and 15 are of the 50 greatest practicable length, the vaporizing tube 14 running the full length of the appa- 55 ratus and being recurred and carried back over about half such length, and the vaporizing tube 15 running the full length of the appa- 60 ratus and being recurred and carried back nearly the full length and then again recurred 65 and carried forward about half such length, as best shown in Fig. 2. Preferably the 70 longer of these two tubes, affording the greater opportunity for perfect vaporization 75 of its contents, is employed for the fuel oil, 80 and the other for the water. The open-end 85 portions of these two vaporizing tubes enter 90 respectively opposite ends of the mixing chamber 16 and are extended far enough

within such chamber to pass each other and 95 respectively approach the opposite end walls 55 of the chamber. By virtue of this arrange- 100 ment, the two different gases formed in the 105 respective vaporizing tubes are impinged against the respectively opposite ends of the 110 interior of the mixing chamber, and rebound- 115 ing from such opposite ends are mixed with 120 superior thoroughness. The fact that they 125 pass out of their respective vaporizing tubes 130 at opposite ends of the mixing chamber, of 135 itself means that each is allowed an opportu- 140 nity to materially spread out and expand be- 145 fore meeting the other, and also that a vortex 150 or rotary motion, peculiarly effective in caus- 155 ing a mixture of the gases, is maintained in 160 the chamber; and both of these effects are 165 greatly increased and promoted by the fur- 170 ther feature of providing that the tube-ends 175 shall pass each other within the chamber so 180 that the two gases will be discharged against 185 the respectively opposite chamber ends and 190 rebound therefrom before the discharges 195 from the two tubes meet each other. The 200 vortex action is further increased and pro- 205 moted by providing that the top and ends of 210 the mixing chamber 16 shall be without any 215 vent, and the mixture of gases shall be drawn 220 off from the bottom of the chamber through 225 the T shaped burner supply pipe 17, so that 230 the heated gases flowing into the mixing 235 chamber shall have an opportunity to rise 240 85 therein and be subjected to the mixing proc- 245 ess for as long a time as possible before the 250 mixture is drawn off and carried to the 255 burners.

The respectively opposite ends of the 90 burner-supply pipe 17 lead, preferably 95 through T shaped connections 18, 18, to 100 the middle portions of the two perforated 105 burner tubes 19, 19, one of which is located 110 beneath and runs the full length of each of 115 the vaporizing tubes, these burner tubes 120 and their perforations being so arranged 125 that the gas mixture emitted through and 130 burning from such perforations shall envelop 135 the vaporizing tubes with its flame and so 140 maintain the vaporization of the fuel and 145 the superheating of its gases within the 150 vaporizing tubes and the mixing chamber. 155 The introduction of the gas mixture into the 160 middle part of each of the burner tubes 165 effects a more perfect and even distribution 170

to the burner perforations 20, 20, than would the introduction of the mixture at either end of such tubes.

The functions of incasing the apparatus and protecting the flames from deflecting drafts and the effecting of the primary ignition of the burners, are provided for by the case-pan 21, whose walls rise somewhat above the burner pipes 19, 19. The bottom 10 of this pan is provided with grooves 22, 22, running around the edges thereof under the burner tubes and across the middle under the burners of the T shaped burner supply pipe 17. These grooves are filled with 15 asbestos wicking, shown therein in section, Figs. 1 and 4, and are designed to distribute under the burners the more volatile oil used for the primary heating of the vaporizing tubes and ignition of the burners. This 20 more volatile oil is supplied to the bottom of the case-pan, preferably at one end, through the ignition-oil supply pipe 23, the latter leading from a suitable receptacle and drop sight-valve, not here shown, and being 25 provided with a shut-off valve 24. The ignition oil supplied to the asbestos wicking in the grooves of the bottom of the case-pan may be ignited at any point, but preferably at the touch-hole 25 at the opposite end of 30 the pan from the ignition oil supply pipe. The grooves for this wicking are preferably cut deeper nearer the intake end, so that the generating or ignition oil may burn the longer at that end of the pan and there 35 effect the more intense heating of the vaporizing tubes. The supply of ignition oil, from the supply pipe 23, is, of course, shut off as soon as the proper initial vaporization of the gases and igniting of the burners has been effected. 40 Thereafter the heat from the burners themselves maintains the vaporization and supply of fuel to the burner flames.

My invention is hereinabove set forth as embodied in a particular form of construction, but is not limited to the particular details thereof or to less than all the possible forms in which the invention as hereinafter claimed may be embodied and distinguished from prior hydro-carbon burners.

50 The apparatus described is intended to be placed bodily in the combustion chamber of stoves, ranges, furnaces and other heaters where the draft is liable to be so strong as to draw the flame away from the burner unless 55 the latter is protected. The case pan is adapted to afford this protection and has been found to be very useful.

The drop feed devices are of novel construction. As shown, they consist of hollow 60 cones 30 having orifices at their apices so small that only a drop can pass at a time. These cones placed in inverted positions, in the top of feed chambers 31 which are of glass are adapted to render the drops plainly

visible. The valves 32 regulate the admission of the oil and water to the cones.

I claim:—

1. In a hydro-carbon burner, in combination, a horizontal mixing chamber, two substantially parallel vaporizing tubes entering 70 respectively opposite ends of said mixing chamber and extending past each other and discharging the vapors of water and oil respectively in opposite directions away from each other, so they do not interfere, burner 75 tubes located below and parallel with said vaporizing tubes, and a pipe connection between said mixing chamber and said burner tubes, substantially as specified.

2. In a hydro-carbon burner, in combination, 80 a horizontal mixing chamber, two substantially parallel vaporizing tubes entering respectively opposite ends of said mixing chamber, the open ends of said tubes being carried past each other within said chamber, 85 and directing the currents away from each other and against opposite end walls of the chamber, burner tubes located below said vaporizing tubes, and a pipe connection between said mixing chamber and said burner 90 tubes, substantially as specified.

3. In a hydro-carbon burner, in combination, a horizontal mixing chamber, two substantially parallel vaporizing tubes having 95 their ends recurved and entering respectively opposite ends of said mixing chamber, the open ends of said tubes being carried past each other within said chamber and directing the vapor in opposite directions, burner tubes located below and parallel with said vaporizing tubes, and a pipe connection between 100 said mixing chamber and said burner tubes, substantially as specified.

4. In a hydro-carbon burner, in combination, a horizontal mixing chamber, two substantially parallel vaporizing tubes having 105 their ends recurved and entering respectively opposite ends of said mixing chamber, the open ends of said tubes being carried past each other within said chamber, and directing the currents of vapor away from each other, burner tubes located below and parallel with said vaporizing tubes, and a pipe connection between the bottom of said mixing chamber and said burner tubes, substantially 115 as specified.

5. In a hydro-carbon burner, in combination, a horizontal mixing chamber, two substantially parallel vaporizing tubes entering 120 respectively opposite ends of said mixing chamber and directing the currents of vapor away from each other, the tube for the oil being doubled twice upon itself to increase its length and to enable it to direct its vapor oppositely to the delivery of the other vaporizing tube, burner tubes located below and parallel with said vaporizing tubes, and a pipe connection between said mixing chamber and

ber and said burner tubes, substantially as specified.

6. In a hydro-carbon burner the combination of a case pan, burner tubes therein, a
5 mixing chamber between and above the burner tubes and having a pipe connection with the latter, and oil and water vaporizing tubes extending over and parallel with the

burner tubes, entering opposite ends of the mixing chamber and extending past each other within the mixing chamber, substantially as and for the purpose described.
